TELEMETERING SYSTEM AND APPARATUS

Ellsworth Albert Hosmer, Kenwood, Jack S. Hawley, Oakland, and Albert E. Jurs, Jr., Berkeley, Calif., assignors, by mesne assignments, to Shand and Jurs Company, Berkeley, Calif., a corporation of California

Application March 16, 1953, Serial No. 342,402

22 Claims. (Cl. 340—359)

This invention relates generally to telemetering systems and apparatus, and particularly to pulse transmitters for use in such systems.

In many instances it is desirable to position an indicator or other member at a receiving station in accordance with the positioning of a member at a remote transmitting station. By way of example, a member at the transmitting station may be positioned in accordance with the location of a float in a liquid tank, and such position indicated at the remote station. In other instances it may be desirable to secure remote readings of temperatures, pressure, flow rates, and like data, to facilitate control of industrial processing operations, or to effect control operations automatically. Telemetering systems making use of regularly spaced control pulses have many desirable characteristics for industrial applications, particularly in that such systems permit use of relatively simple pulse generating equipment and relatively simple step by step operating means at the receiving station for the positioning of an indicator or like member in accordance with the number of received pulses. Such a pulse telemetering system is disclosed in co-pending application Serial No. 307,444, filed September 2, 1952, now Patent No. 2,748,373, in the name of E. A. Hosmer. One problem involved in such telemetering equipment is the construction of the transmitter for generating the transmitted pulses. The transmitter should be relatively accurate with respect to control of the transmitted pulses, to obtain reasonable accuracy in the positioning of an indicator or like member at the receiving station. It should not be unduly complicated in its electrical or mechanical construction, and it should be capable of use over long operating periods without an undue amount of servicing or repair. It is also desirable that the transmitter be a relatively compact assembly which can be readily installed with other industrial equipment, as for example with liquid tank gauging equipment as previously mentioned. Insofar as we are aware, no transmitter unit is available which will fulfill these requirements.

It is an object of the present invention to provide a novel transmitter for use in telemetering systems of the pulsing type, which functions automatically to generate pulses in a predetermined manner.

Another object of the invention is to provide a transmitter of the above character which will provide means for automatically transmitting an identifying code signal, in addition to transmitting position indicating pulses.

Another object of the invention is to provide a transmitter of the above character which is relatively accurate with respect to its generation of pulses, and which will therefore contribute to the over-all accuracy of a telemetering system.

Another object is to provide a transmitter which is capable of transmitting pulses which indicate position in two units, such as feet and inches.

Another object of the invention is to provide a novel transmitter which is not unduly complicated in either its electrical or mechanical features, and which is capable of use over long operating periods without undue servicing or repair.

2

Another object of the invention is to provide a transmitter of the above character which is completely automatic in its operation, and which carries out a complete cycle of operation after receiving a triggering pulse.

Further objects and features of the invention will appear from the following description in which the preferred embodiment has been set forth in detail in conjunction with the accompanying drawing.

Referring to the drawing:

Figure 1 is a side elevational view in section of one embodiment of our invention illustrating a transmitter unit incorporating the present invention.

Figure 2 is an end view showing the operating parts within the enclosing housing of Figure 1, and taken as indicated by the line 2—2 of Figure 1.

Figure 3 is a cross-sectional view taken along the line 3—3 of Figure 1.

Figure 4 is a cross-sectional view taken along the line 4—4 of Figure 1.

Figure 5 is a cross-sectional view taken along the line 5—5 of Figure 1.

Figure 6 is an enlarged detail in section taken along the line 6—6 of Figure 1.

Figure 7 is an enlarged detail in section taken along the line 7—7 of Figure 1.

Figure 8 is a detail in section taken along the line 8—8 of Figure 1.

Figure 9 is a cross-sectional view taken along the line 9—9 of Figure 1, and indicating only the upper half of the unit.

Figure 10 is a view like Figure 9 and taken along the line 10—10 of Figure 1.

Figure 11 is a cross-sectional detail taken along the line 11—11 of Figure 2.

Figure 12 is an enlarged detail of the embodiment in Figure 1 illustrating one of the multi-contact switches and its operating means.

Figure 13 is an end view of the multi-contact cam operated switch of the embodiment in Figure 1.

Figure 13A is a cross-sectional detail taken along the line 13A—13A of Figure 13.

Figure 14 is a circuit diagram serving to schematically illustrate the electrical and mechanical features of the embodiment in Figure 1.

Figures 14A to 14D, inclusive, are schematic views of the embodiment in Figure 1, showing certain cams in various operating positions at different points of a complete cycle.

Figure 15 is an end view as in Figure 2 of another embodiment of our invention.

Figure 16 is a detail in section taken along the line 16—16 of Figure 15.

Figure 17 is a circuit diagram serving to schematically illustrate mechanical and electrical features of the embodiment in Figure 15.

The transmitter illustrated in the drawings, Figures 1 to 14D inclusive, consists of a base plate 10 (Figure 1) which serves to mount the various working parts. A positioning shaft 11 extends through and is journaled to the base. It is the angular positioning of this shaft which one desires to transmit by way of control pulses to the receiving station.

Various appliances can be connected to the shaft 11 to determine its positioning. By way of example the shaft is shown schematically connected to liquid tank gauging equipment. This equipment can include a float (not shown) located within a liquid storage tank (not shown) and connected to the lower end of a perforated metal gauging tape 12 (Figure 4). Exterior of the tank, the tape passes through the casing 13, where it is tracked over the guide rollers 14 and 15 and the intermediate

sprocket wheel 16. The spaced perforations of the tape register with the studs 17 provided on the wheel 16. The tape can be urged against the periphery of the wheel 16 by suitable means such as the resilient endless belts 18. The wheel 16 is directly connected to the shaft 11, and the length of the tape extending beyond the casing 13 is attached to suitable take-up counterbalancing means, as a weight or a spring urged take-up reel.

Upon one side of the base plate 10, which is enclosed by the removable housing 21, there is another stationary mounting plate 22 which is attached to the plate 10 by the mounting studs 23. A bushing 24 is mounted upon plate 22 and serves to journal the shaft 26. Carried loosely on this shaft are the wheels or discs 27 and 28. These discs can be formed of suitable material such as an insulating material for disc 27 and brass for disc 28.

Disc 28 has a direct 1 to 1 drive connection to shaft 11. Thus, it is mounted upon a bushing 29 that is journaled on the shaft 26, and which carries a gear 31. Gear 31 meshes with the gear 32 that is fixed to the shaft 11. The discs 27 and 28 are operably connected whereby for each revolution of disc 28, disc 27 is advanced a small angular increment. Thus a Geneva pinion 33 serves to operatively connect the two discs, and this pinion is carried by the journal means 34. The pinion is retained against the longitudinal movement by suitable means such as the abutment 36 and the abutment plate 38. One portion 33a of the Geneva pinion (Figure 1) may be formed as an ordinary spur gear pinion, and the teeth of this portion engage the teeth 39 formed on the periphery of disc 27 (Figures 1, 8 and 9) and the teeth 41a of the Geneva transfer block 42a (Figures 6 and 10) carried near the periphery of disc 28. Another portion 33b of the Geneva pinion can be formed with relatively few teeth (Figures 7 and 10) that are adapted to operate within a notch 41b formed in the periphery of the disc 28 and in the block 42b.

The form of pinion portion 33b is such that when the notch 41b is not in operating position and the teeth 41a are not engaged with the Geneva pinion, the Geneva pinion 33 is locked in a fixed position by action of the teeth of pinion portion 33b coming in contact with the periphery of disc 28 as shown in Figure 7.

The discs 27 and 28 serve to mount certain electrical contacts which can be referred to as sweep contacts. Thus, one contact 43 is carried by the spring arm 44, which in turn is mounted on the disc 27. It is electrically connected to the brush contact 46 that engages the slip ring 47. The slip ring has an insulated mounting on the sleeve 24, and is electrically connected to the circuit illustrated in Figure 14, as will presently be explained.

For the disc 28 there is a contact 48 carried by the insulated spring arm 49. A metal slip ring 51 is carried by the disc 28, and is electrically connected to the contact arm 49 by the stud 52. Suitable insulating means serves to mount the slip ring 51 on disc 28 to prevent its grounding to the shaft or to other adjacent metal parts. The slip ring 51 is engaged by the stationary brush contact 53 that has an insulated stationary mounting 54, and which likewise is connected in the electrical circuit.

Cooperating with both of the contacts 43 and 48, there is a sweep contact arm 56. This arm is directly mounted by collar 57 upon the metal shaft 26, and is therefore grounded to the metal parts of the apparatus. Assuming rotation of shaft 26, arm 56 swings through an arc such that it is brought into electrical engagement with contacts 43 and 48, at positions depending upon the angular positioning of the discs 27 and 28.

Pulse generating contacts 61 and 62 are provided in conjunction with the cam 63 (Figure 2) for generating the pulses to be transmitted. These contacts are carried by the spring arms 64 and 66, which are supported by the insulated mounting 67. The normal spacing between the contacts can be adjusted by the set screw 68. The shap-

ing of cam 63 is such that a substantial period of dwell is provided after the contacts 61 and 62 are closed. Also the valleys provide a substantial space period between periods of closure, thus providing the desired time spacing between pulses.

Suitable means is provided for driving the cam 63, such as an electric alternating current motor 69 of the self-starting synchronous or shaded pole type (Figures 3 and 11). The pulsing cam 63 is mounted on the hub 65 (Figure 11) together with gear 70 and pinion 71 and the hub is journaled to the stud 72. Speed reducing gearing connects the cam 63 to the motor shaft, including the pinion 73 which is attached to the motor shaft, gear 74 which meshes with pinion 73, and pinion 75 which is fixed to the gear 74 and which meshes with the gear 70. The speed with which the cam 63 is driven is such as to provide the desired rate of pulse transmission. With the equipment which we have constructed, a pulse rate of the order of 8 pulses per second has been found satisfactory. Each pulse was $\frac{1}{16}$ of a second duration, thus providing a spacing between pulses of $\frac{1}{16}$ of a second. This rate can be varied over a wide range, the limiting factors arising in associated equipment.

The same motor 69 is employed to turn the shaft 26 and the sweep arm 56. The gear train for this purpose includes a gear 78 which is driven by pinion 71 (Figures 2 and 11), a pinion 79 which is directly connected to gear 78, and a gear 81 (Figures 1 and 2) which is mounted upon a hub 82 and connected to drive the shaft 26. Suitable means can be imposed in this gear train to apply a predetermined amount of friction braking such as a light compression spring 83 interposed between one end of pinion 79 and the lock nuts 84 on the stud 86 upon which this pinion is journaled.

A cycling cam 87 (Figure 2) is also mounted to rotate together with shaft 26. Thus, this cam is shown carried by the shaft adjacent the one side of the gear 81, and coupled to the gear by means of screws 88 which are mounted upon the gear and which extend into openings 89 provided in the cam.

The peripheral surface of the cam 87 is circular except for the notches 91, 92 and 93 (Figure 2). The cam serves to operate a multi-contact switch designated generally as S_1 . Switch S_1 consists of the spring arms 96, 97, and 98 (Figure 12) which are carried by the insulating mounting 101a and spring arm 99 mounted on the metal block 101 and grounded by it. The free end of spring arm 96 carries a foot or pad 102 (Figures 13 and 13A) for engaging the periphery of the cam 87. The free end of the spring arm 99 likewise carries a foot or pad 103, for engaging the cam surface. Foot 103 extends slightly beyond foot 102 so that as the two ride over the shoulder of a notch in the cam 87, 102 drops first and then is followed by 103. The stressing of spring arms 96 and 99 is such that 102 and 103 are urged against the peripheral surface of cam 87. Stressing of spring arms 97 and 98 is such that when foot 102 drops, contacts o and p are open until foot 103 drops. Spring arm 96 also carries an insulating pad 104, serving to elevate spring arm 97 when the arm 96 is raised. Cooperating electrical contacts 106 and 107 are carried by spring arms 97 and 98, and cooperating contacts 108 and 109 by the spring arms 98 and 99.

Insulated mounting 101b carries a switch designated generally as S_2 and which includes the spring arms 112, 113, 114, and 115 and spring arm 111 which is grounded on metal block 101. These spring arms are provided with contacts 116, 117, 118, 119, 120, and 121. The contacts 117 and 119 are mounted upon the same spring arm 113. Spring arm 113 also carries an insulating pad 122 serving to elevate spring arm 114 when arm 113 is raised.

The contacts of switch S_2 are operated by the pin 123, carried by the latch 124. One end of this latch is provided with a slot 126 to loosely accommodate the mount-

ing pin 127. The latch is operated by a rotating cam 128, which is mounted upon the stud 129 together with its operating gear 131 (Figure 1). Gear 131 meshes with the pinion 132 which is fixed to rotate with the shaft 26. The gear ratio is such that the cam 128 makes one complete revolution for two complete revolutions of the cam 87.

The cam 128 rotates in a counter-clockwise direction as viewed in Figure 2, while the cam 87 revolves in opposite direction (i. e. clockwise as viewed in Figure 2). The periphery of cam 128 is provided with the notch 133, adapted to accommodate the cam lug 134 on the latch 124. The lug 134 is such that it drops down over the cam shoulder 136, as the cam 128 rotates, and the lug has an inclined camming face 137 adapted to be engaged by the camming face 138 on the rotary cam 128 to force the latch 124 upwardly, and with a force component to the left as viewed in Figure 2. The latch is yieldably urged downwardly and toward the right as viewed in Figure 2, by the tension spring 139. The arrangement of the cam 128 with respect to the latch 124 is such that as the cam revolves (counter-clockwise as in Figure 2) the latch is cammed upwardly, whereby the pin 123 operates the switch S₂. It may be explained that such operation takes place before the foot operation is commenced. Thereafter the latch remains in a raised position until the end of a complete cycle of operation, at which time the cam 128 has made substantially one complete revolution and has rotated to a position where the latch can drop down to substantially the position illustrated in Figure 2.

Means is provided whereby the latch, in its raised position, locks the Geneva transfer pinion. Thus a gear 141 (Figures 1 and 12) meshes with one end of the Geneva pinion 33, and is journaled on the stud 142. A toothed ratchet-like wheel 143 is fixed to the gear 141, and is adapted to be engaged by the pawl 144, formed on the upper edge of the latch 124 (Figures 2 and 12). The arrangement is such that when the latch is raised, the pawl 144 engages with one of the teeth of the ratchet wheel 143, thus locking this wheel and the Geneva pinion against further rotation. The lost motion of the latch 124 with respect to its mounting stud 127 insures locking engagement with the toothed wheel 143 when the pinion 33 is in a position that it might occupy while transferring motion to the wheel 27. The locking of pinion 33 locks the foot wheel 27 but allows the inch wheel 28 to follow the fluid level within the limits of one foot.

It may be desirable to have means actuated by latch 124 to frictionally engage both the foot and the inch wheels so as to lock them before the reading operation.

The operation of latch 124 prevents errors in reading greater than one increment of the inch wheel which in the embodiments of our invention would be one-eighth of an inch. This is accomplished by the following operation: If latch 124 finds pinion 33 in the position where it is transferring an additional increment to the foot wheel, it will when cammed upward, and forward, if necessary, move toothed wheel 143 to one position or the other depending on which is nearer. One direction would carry the foot disc 27 to the next increment and place the inch disc 28 at its minimum or zero. The other position would return the foot wheel to the previous increment and the inch disc to its maximum or 11 $\frac{1}{8}$ inches. This prevents incorrect readings and assures that the transmission of the foot pulses will be terminated at the end of a full pulse, and prevents the transmission of a partial pulse which would occur if the foot wheel were changing from one increment to another.

The engagement of latch 124 with toothed wheel 143 also serves to fix the relationship between the foot and the inch wheels so that fluid fluctuations that might occur during a reading will not give rise to incorrect readings (e. g. at the time the reading was instigated the fluid level could be 6 feet 11 $\frac{1}{8}$ inches, then the transmitter would trans-

mit the pulses indicating 6 feet and before the inches could be transmitted, the level could then rise to 7 feet 0 inches, whereby pulses indicating 0 inches would be transmitted causing an error of nearly a foot in the reading). Errors which could occur by the liquid falling during the reading operation are also prevented in the same manner.

In addition to the switches previously mentioned, the mounting 101a supports a spring arm 146 carrying contact 147 which is electrically connected to spring arm 98 (Figures 2 and 12). This contact is adapted to engage the face of the metal cam 128, and is thus grounded upon the same. At one point the face of the cam 128 carries a small area or spot 148 formed of insulating material, which at a certain point in the rotation of the cam 128 engages the contact 147 to interrupt grounding of the spring arm 146. This point corresponds to substantially one-half revolution of the cam 128 from its starting position.

Acting in conjunction with cam 87 is an additional switch arm 151 which is adjustably secured by attaching means 152 to the metal strip 153. Attaching means 152 also serves to ground switch arm 151 to shaft 26. The contact 154, carried by the free end of the spring arm 151, is adapted to engage the contact 155, which is located on one side of the spring arm 96 (Figure 13). The angular setting of the spring arm 151 with respect to the cam 87 determines the number of coding pulses which are transmitted prior to transmission of the indicating pulses.

In addition to the electrical parts previously described, the plate 22 forms a convenient mounting for a plurality of multi-contact relays R₁, R₂, R₃ and R₄, which are utilized in the electrical circuit.

In Figure 14 certain of the mechanical parts have been illustrated schematically to facilitate explanation. Instead of applying separate numerals to the various contacts of the relays R₁, R₂, R₃ and R₄, the cooperating sets of contacts have been designated by lower case letters a to n, inclusive (except j). The various sets of contacts on the switches S₁ and S₂ have likewise been designated by lower case letters o to t, inclusive. The switch comprising spring arm 146 and the cooperating cam 128 is designated as S₃, and the cooperating contacts by lower case letter u. The contact 43 carried by the foot wheel, together with the sweep arm 56, has been designated as switch S₄ and its cooperating contacts by the lower case letter v. The contact 48 carried by the inch wheel 28, in conjunction with the sweep arm 56, has been designated as switch S₅ and the effective cooperating contacts by lower case letter w. The pulsing contacts have been designated as switch S₆, and its cooperating contacts by lower case letter x.

Telegraph lines T₁ and T₂ (Figure 14) extend to the receiving station. As is understood by those familiar with telegraphic circuits, one of these lines can be omitted by using a ground return. Lines L₁ and L₂ represent a local source of alternating current supply, such as the standard 110 volt A. C. The power supply is connected to both the primary of the transformer 157 and to the motor 69 which are in series with contacts a of relay R₁, said contacts a being in parallel with contacts d of R₂ and contacts r of S₂. One side of the transformer secondary is grounded (i. e. connected to the metal frame of the transmitter unit) and the other side connects to one terminal of the coil for relay R₂, and also to the corresponding terminals of relays R₃ and R₄.

In general relay R₁ can be termed a triggering relay. Its purpose is to close the circuit for supplying 110 volts to the transformer 157 and motor 69, and to condition the relays R₂, R₃ and R₄ for operation. The purpose of relay R₂ is to sustain the supply of 110 volt alternating current to the motor and transformer after the relay R₁ has been released (i. e. deenergized) and to prevent false signals during certain portions of the operating cycle. The purpose of relay R₃ is to selectively condition the circuit for the transmission of either code pulses and

feet pulses, or inch pulses. Relay R_4 is a gating relay which serves to establish and terminate the pulses.

Operation of our apparatus can now be described as follows: It is assumed that the lines T_1 and T_2 are connected to a remote receiving station which includes a battery or other suitable supply indicating means, operated step by step in response to the receipt of pulses, and means for transmitting a starting pulse to the sending station. The means at the receiving station can be substantially as disclosed and claimed in copending application Serial No. 307,444, filed September 2, 1952.

It may be found desirable to provide a self-contained source of signalling voltage within the sending station instead of the receiving station.

Figures 14A to 14D inclusive, schematically illustrate the positioning of certain operating parts of the apparatus at different points in a complete operating cycle. Particularly they show the relative positioning of the cams 87 and 128, together with the latch 124 and the toothed wheel 143. In Figure 14A the parts are illustrated in the positions which they occupy at the beginning of an automatic cycle. At that time motor 69 and transformer 157 are de-energized, and all of the relays R_1 , R_2 , R_3 , and R_4 are de-energized or released. Before outlining the positions illustrated in Figures 14B, 14C and 14D, it may be explained that a complete operating cycle serves first to transmit pulses to the receiving station over the lines T_1 and T_2 . These pulses serve as in identification and therefore can be referred to as coding pulses. The pulses are effectively transmitted by placing an intermittent direct short circuit between lines T_1 and T_2 , by closing and opening the pulsing contacts x . The number of pulses transmitted for identification is determined by the angular setting of the arm 151 relative to the cam 87. In a typical system one can provide for 20 or more pulses for such coding purposes.

After coding pulses have been transmitted there is a short pause, after which pulses are transmitted to indicate the position of the foot wheel 27. The number of pulses is determined by the angle through which the contact arm 56 sweeps from a base position before it engages the contact 43 carried by foot wheel 27. Following transmission of the foot pulses, the cam 87 completes the first revolution, and then during its second revolution pulses are transmitted in accordance with the angle through which the arm 56 sweeps before it engages the contact 48, carried by the inch wheel 28. After transmitting the so-called inch pulses, the cam 87 returns to its initial position, after which the apparatus is returned to rest in the same condition as it was before it was started.

As previously stated the apparatus is started in operation by a starting or triggering pulse transmitted over the lines T_1 and T_2 from the receiving station, and this starting pulse provides sufficient voltage to energize the coil or relay R_1 . It will be noted that this winding is connected across the lines T_1 and T_2 , in series with the contacts e of relay R_2 . When relay R_1 is energized, its contacts a , b and c are closed. Because contacts a are connected in series with the power supply L_1 and L_2 , and the motor 69 and transformer 157, the closing of contacts a supplies current to both the motor and the transformer, whereby the motor is started in operation to drive the pulsing cam 63, cams 87 and 128, and the sweep contact arm 56.

Closing of contacts b of relay R_1 together with energizing the transformer 157 supplies current to the coil of relay R_4 whereby this relay is operated. The circuit is completed from the transformer through the coil of relay R_4 , and through the contacts b of relay R_1 to ground. Upon operation of this relay its contacts m and n are closed, while contacts l are opened. Closing of contacts n completes a holding circuit to continue holding current through the coil of relay R_4 , or in other words to latch

this relay in operated (i. e. energized) position. The holding circuit is completed from the transformer through the coil of relay R_4 , through contacts n , and through the contacts o and p of switch S_1 to ground. Closing of contacts m of relay R_4 completes an energizing circuit for the coil of relay R_2 which is completed from the transformer through the relay coil of R_2 , through contacts c of relay R_1 , and then through the contacts m of relay R_4 to ground.

Simultaneously with the operation of relay R_2 , relay R_3 is energized. The energizing circuit for the relay coil of relay R_3 is completed from the transformer through the relay coil of relay R_3 , through the contacts s of switch S_2 , through contacts c of relay R_1 , through the contacts m of relay R_4 to ground.

A holding circuit for relay R_3 is then completed from the transformer through the coil of relay R_3 through the contacts k of relay R_3 , through the contacts o of switch S_1 to ground. A holding circuit for relay R_2 is completed from the transformer through the relay coil of R_2 through contacts s of switch S_2 , through contacts k of relay R_3 through contacts o of switch S_1 to ground.

When relay R_2 is operated the opening of its contacts e interrupts the coil circuit for relay R_1 , whereby relay R_1 is released. Upon its release all of its contacts a , b and c are opened.

Although the motor 69 is driving the pulsing cam 63 as soon as it is energized, no pulses are transmitted over the line up to this time because the contacts l of relay R_4 are opened as soon as relay R_4 is energized which occurs immediately after the motor has been energized and before contacts f of relay R_2 are closed.

When the cam 87 has been rotated a sufficient amount by motor 69 to cause the switch foot 102 on spring arm 96 to drop into the notch 92 (i. e. operation of switch S_1) the parts are substantially in the position illustrated in Figure 14B. The cam 128 is now camming the latch upwardly to a position just short of locking position with the toothed wheel 143. When switch foot 102 drops down into notch 92, contacts o and p of switch S_1 are opened momentarily until foot 103 on spring arm 99 drops down upon further rotation of cam 87. The momentary opening of contacts p interrupts the holding circuit of relay R_4 by removing contact 106 (the lower contact of contacts p) on spring arm 97 from ground. The momentary opening of contacts o does not affect the holding circuit of relay R_3 because a ground is maintained by S_3 (contact 147 on spring 146 maintaining contact with grounded cam 128).

Contacts o and p are closed by the further rotation of cam 87 as pointed out above, however, this does not re-energize relay R_4 because contacts n are now open.

At this time relay R_4 is conditioned to be operated by grounding of contacts q (grounding occurs by contact 154 on arm 151 coming in contact with contact 155 mounted on foot 102 of spring arm 96) or contacts v (grounding occurs by contact 43 on foot disc 27 coming in contact with sweep arm 56). A circuit is completed from the transformer through the coil of relay R_4 through contacts h of relay R_3 through contacts q or v to ground.

The above-mentioned momentary operation of switch S_1 (i. e. dropping of feet 102 and 103) occurs during an open period of the contacts x whereby relay R_4 will be released during that interval so that only complete pulses will be transmitted. This same timing relationship also takes place before the sending of the foot pulses and also the inch pulses described subsequently.

As described above, the dropping of feet 102 and 103 into notch 92 of cam 87 releases relay R_4 and initiates transmission of coding pulses being generated by contacts x due to rotation of cam 63. The circuit for transmission of the pulses is from line T_1 through contacts f of relay R_2 , through contacts l of relay R_4 , through contacts x of switch S_6 to line T_2 .

The apparatus continues to transmit coding pulses until

contacts *q* are closed. As previously stated, this is dependent upon the position of the arm 151 relative to the cam 87. In a typical instance five pulses can be transmitted to disclose the identity of the transmitting station to the receiver. Such identification is desirable where a number of transmitters may be selectively connected to a single receiving station. As previously mentioned, when contacts *q* are closed, current is supplied to the coil of relay R₄ whereby this relay is operated to break its contacts *l*. The opening of these contacts interrupts further transmission of pulses. Relay R₄ is again latched in operated position by closing of holding contacts *n* of relay R₄.

During the period allotted for transmission of code pulses, the latch 124 is being cammed upwardly to lock the ratchet wheel 143, and to effect operation of switch S₂. This camming action is shown in Figures 14A, 14B and 14C. In the operation of this switch contacts *t* and *r* are closed, and contacts *s* are opened. Closing of contacts *r* insures resumption of current to the transformer from the 110 volt power supply, because these contacts are in parallel with the contacts *d* of relay R₂. This is desirable because of the probability that relay R₂ may be released by momentary power failure. This prevents the Geneva pinion 33 from remaining locked after resumption of power. Also if power has been interrupted during the reading operation, the contacts *r* return the device to its starting position because they sustain a power circuit to the motor independent of relay R₂.

The closing of contacts *t* of switch S₂ is accompanied by opening of contacts *s* and the opening of these contacts serves to interrupt the holding circuit for relay R₂ through contacts *k* of relay R₃ and is thus only sustained by contacts *t* of switch S₂. The action is such that contacts *t* close before contacts *s* open.

After a suitable interval after the coding pulses have been terminated by closing of contacts *q*, switch S₁ operates again by dropping into notch 93 and releases relay R₄ as before whereby the pulsing contacts *x* are connected to lines T₁ and T₂ to secure a foot indication. Actually the number of such pulses transmitted indicates the angular position of wheel 28 from a base starting point. The pulses are transmitted until the sweep arm 56 engages the contact 43. On the circuit diagram of Figure 14 this corresponds to closing of the contacts *v*, which again completes the energizing circuit through the coil of relay R₄, through contacts *h* whereby the holding circuit through contacts *n* is again energized and contacts *l* opened to discontinue further transmission of pulses.

In the preferred form, the gearing between cam 63 and sweep arm 56 is such that one closure of contacts *x* (i. e. transmission of one pulse) occurs for each increment of displacement represented on each of the foot and inch wheels. It may be desirable to transmit fewer or more pulses for each increment measured in certain applications.

The apparatus now continues to operate, with continued rotation of the cam 87, until it has completed nearly one revolution from its starting point. Now switch S₁ is again operated by the notch 91, whereby the opening of contacts *p* again releases relay R₄. However, this time the opening of contacts *o* by operation of switch S₁ also interrupts the holding circuit for relay R₃ because a ground is no longer sustained by switch S₃ because it is now in contact with insulating spot 148.

Continued rotation of cam 87 closes contacts *o* and *p* but switch S₁ will no longer have any electrical effect on the apparatus for the remainder of the reading operation because contacts *p* are now grounded through contacts *i* of relay R₃, and contacts *o* are again grounded through switch S₃ as it has moved from the insulating spot 148.

Since relay R₄ is now in a released condition, the apparatus now proceeds to transmit pulses indicating the position of the inch wheel 28. This transmitting condition continues until the sweep arm 56 moves from an

initial base position to a position where it engages contact 48 on the inch wheel 28 and thereby energizes relay R₄ by completing a ground through contacts *g* of relay R₃ to contacts *w* on the inch wheel 28, which in turn 5 interrupts the transmission of pulses by opening of contacts *l* on relay R₄. The holding circuit for relay R₄ is again energized by the contacts *n*.

Toward the end of the second complete revolution of cam 87, cam 128 is completing its first revolution. The 10 return of cam 128 to substantially its initial starting point causes the latch 124 to snap down over the shoulder 136, to release the ratchet wheel 143 and the Geneva transfer pinion, and to effect an operation of switch S₂. This occurs after the time that the switch S₁ engages the notch 91 on the second revolution of cam 87. The 15 time interval between the transmission of the inches and the shut down of the equipment is to allow the receiver (not shown) to sense that the transmitting operation has been completed. Operation of switch S₂ causes the contacts *t* to be opened, which serves to interrupt the holding circuit for the relay R₂. The power supply for the motor 69 and the transformer 157 is interrupted by the breaking of contacts *d* of relay R₂ caused by the de-energization of relay R₂ and by breaking of contacts *r* of switch S₂ 20 caused by the dropping of pawl 124.

As pointed out previously, the purpose of relay R₂ is to prevent false signalling during certain portions of the reading operation, namely the period following the complete cycle after the power circuit to the apparatus has 25 been broken; but while the cam 63 is still in motion due to the momentum of the various driven parts. This false signalling is prevented by the opening of contact *f* of relay R₂.

After de-energization of both the motor and the transformer, the apparatus coasts to a stop substantially in the 30 position illustrated in Figure 14A. The apparatus is then in a position to be energized for another reading operation.

Another embodiment of our invention is shown in 35 Figures 15 to 17 inclusive. It is the purpose of this embodiment to transmit pulses indicating coarse and fine units simultaneously by the use of three wires, one of which can be a ground return, whereas, in the embodiment shown in Figures 1 to 14D inclusive, it is only 40 possible to transmit pulses indicating coarse and fine units sequentially.

The embodiment of our invention for transmitting pulses simultaneously is substantially the same as illustrated in Figures 1 to 14D except for the changes shown 45 in Figures 15 to 17 inclusive. The major changes are that cam 87a has been interchanged for cam 87, cam 128a for 128, insulating spot 148a for 148, insulating pin 123a for pin 123, switch S₇ for switch S₁ and switch S₈ for switch S₂.

It will be noted that cam 87a serves to operate a switch 50 designated generally as S₇ which consists of spring arms 171 and 172 which are carried by the insulated mounting strip 101a. Spring arm 171 carries electrical contact 173 and spring arm 172 carries electrical contact 174. 55 Spring arm 171 also carries member 175 for engaging the cam 87a.

Insulated mounting strip 101b carries a switch designated as S₈ which consists of spring arms 176, 177, 178 and 179 which are provided respectively with contacts 180, 181, 182 and 183. Spring arms 177 and 179 are 60 also provided with a pad 184 which serves to raise the spring arm 179 when spring arm 177 is raised. All of the contacts of switch S₈ are operated by the insulating pin 123a carried by the latch 124.

As in the previous embodiment, the cam 128a makes one complete revolution for two complete revolutions of cam 87a. The cam 128a rotates in a counter-clockwise direction as viewed in Figure 15, while cam 87a revolves in a clockwise direction.

70 By way of example, in one typical instance cam 87a

was made to rotate at a speed of 5 revolutions per minute and cam 128a to rotate at 2½ revolutions per minute. Using such a speed, and by placing cam 87a in a starting position as shown in Figure 15 (120° from the position where it will operate switch S₇), it is possible to receive a trigger pulse up to 3 seconds in duration. Insulating spot 148a on cam 128a was placed in such a position that it would be electrically in contact with switch S₃ at the second operation of switch S₇ by cam 87a. To accomplish this insulating spot 148a was placed 240° from the position where it would come into contact with switch S₃. With this timing relationship, latch 124 will rise in approximately 2 seconds to operate switch S₈ after receipt of the triggering pulse and switch S₇ will operate within 4 seconds after receipt of the pulse.

In the embodiment of our invention shown in Figure 15, multi-contact relays R₅, R₆, R₇ and R₈ are mounted on plate 22 and have been substituted for relays R₁, R₂, R₃ and R₄.

Figure 17 is a circuit diagram of this embodiment with a schematic illustration of certain mechanical parts to facilitate explanation. The cooperating sets of contacts on relays R₅, R₆, R₇ and R₈ have been designated by the lower case letters aa to hh. The various sets of contacts on the switches S₇ and S₈ have likewise been designated by the lower case letters ii to kk. The switch comprising spring arm 146 and cooperating cam 128a is designated as switch S₃ and the cooperating contacts by lower case letter u as in the previous embodiment. The remainder of the contacts remain unchanged from the previous embodiment.

Telegraph lines T₃, T₄ and T₅ (Figure 17) extend to the receiving station. As is understood by those familiar with telegraphic circuits, the common return line T₅ can be omitted by using a ground return. Lines L₃ and L₄ represent a local source of alternating current supply such as the standard 110 volts A. C. The power supply is connected to both the primary of transformer 157 and to the motor 69, both of which are in series with contacts aa of relay R₅. Contacts aa are also in parallel with contacts kk of switch S₈. One lead of the transformer secondary is connected to contact dd of relay R₆ and also to spring arm 171 of switch S₇. The other lead of the transformer secondary is connected to one terminal of the coil of relay R₆, and also to the corresponding terminals of the coils of relays R₇ and R₈.

In general relay R₅ can be termed a triggering relay and its purpose is to close the circuit for supplying power to the transformer 157 and the motor 69 during receipt of the triggering pulse. Relay R₆ may be termed a signal starting relay as it serves to initiate transmission of foot and inch pulses over lines T₃, T₄ and T₅ and also to sustain a ground through contacts dd and thereby conditioning relays R₇ and R₈ for operation. Relay R₇ may be termed the foot relay as its operation terminates the sending of foot pulses, and relay R₈ may be termed the inch relay as its operation terminates the sending of the inch pulses.

Operation of the embodiment shown in Figure 17 may now be described as follows: It is assumed that lines T₃, T₄ and T₅ are connected to a remote receiving station which includes a battery, indicating means operated step by step in response to the receipt of pulses, and means for transmitting a starting pulse to the sending station.

The operation is commenced by sending a starting pulse to the sending station over lines T₃ and T₅ to energize the coil of relay R₅ whereby relay R₅ is operated. This circuit is completed from line T₃ to normally closed contacts jj of switch S₈ through the coil of relay R₅ and then to line T₅.

The operation of relay R₅ closes contacts aa which energize the motor 69 and the transformer 157. This circuit is completed from line L₃ to contacts aa of relay R₅ and thence in parallel through the motor and the transformer to the line L₄.

Starting of the motor 69 starts cams 63, 87a, 128a and sweep arm 56 into operation. After a suitable interval cam 128a starts camming latch 124 upward as shown in Figure 14B whereby switch S₈ is operated. As switch S₈ is being operated, contacts kk are first closed, and since these contacts are in parallel with contacts aa of relay R₅, they will serve to sustain the power to the transformer and the motor after relay R₅ has been released and contacts aa opened. Further operation of switch S₈ serves to open contacts jj which serves to break the energizing circuit for relay R₅. As described in the previous embodiment, further camming upward of latch 124 serves to lock the Geneva pinion 33 during the remainder of the reading operation.

After a suitable interval subsequent to the operation of switch S₈ and the locking of Geneva pinion 33, cam 87a comes in contact with member 175 on spring arm 171 thereby engaging switch S₇ and closing contacts ii momentarily. This momentary closing of contacts ii grounds one of the secondary leads of transformer 157. This circuit is completed from one transformer secondary lead to contacts ii of switch S₇ to switch S₃ which is grounded on cam 128a except when it is in contact with insulating spot 148a which it is not at this time. Since one side of the coil for relay R₆ is grounded and the other side of the coil is connected to the ungrounded transformer secondary lead through contacts ii, the coil of relay R₆ is energized whereby relay R₆ is operated which in turn closes the contacts bb, cc, and dd. Closing of contacts dd energizes a holding circuit for relay R₆ thereby securing the continued operation of relay R₆ even after contacts ii on switch S₇ are opened. This holding circuit is completed because contacts dd of relay R₆ continue to sustain the ground initiated by contacts ii of switch S₇. This sustained grounding of one lead of the transformer secondary serves to place relays R₇ and R₈ in a position to be operated by grounding one side of their coils as the other side is connected to the ungrounded secondary lead of transformer 157.

It must be borne in mind that as soon as the motor 69 is energized by the closing of relay R₅, the cam 63 starts operating switch S₆ so that contacts x are continuously opened and closed. However, no pulses are transmitted over the lines T₃, T₄ and T₅ until relay R₆ is operated because contacts bb and cc of relay R₆ are normally open. However, as soon as relay R₆ is closed, foot and inch pulses are transmitted over the lines T₃, T₄ and T₅ simultaneously.

The circuit for sending the foot indication is from line T₃ through contacts bb of relay R₆ through normally closed contacts ee of relay R₇ through pulsing contacts x of switch S₆ to line T₅. The circuit for sending the inch indication is from line T₄ to contacts cc of relay R₈ to normally closed contacts gg of relay R₈ through pulsing contacts x of switch S₆ to line T₅.

Cam 87a has been so positioned that it will operate switch S₇ to close contacts ii at such a time that the contacts x of switch S₆ are open so that transmission of foot and inch pulses will start at the beginning of a pulse rather than at any other part of a pulse. Sweep arm 56 is so positioned in relation to cam 87a that it is at the reference or zero point of the foot wheel 27 and the inch wheel 28 at the time cam 87a operates switch S₇ to close contacts ii to operate the relay R₆. Therefore, the foot and inch pulses are commenced at the time the sweep arm 56 is at the reference or zero position.

The transmission of the foot and inch pulses over lines T₃, T₄ and T₅ continues until each series is respectively terminated. The foot pulses are terminated by the sweep arm 56 coming in contact with contact v on the foot wheel 27 whereby one end of the relay coil of relay R₇ is grounded thus completing a circuit through the coil of relay R₇ and operating relay R₇. This circuit for energizing relay R₇ is completed because one secondary lead of transformer 157 is grounded through contacts dd of

relay R_6 and the other secondary lead is grounded through the coil of relay R_7 through contacts v to grounded sweep arm 56.

This operation of relay R_7 serves to open the normally closed contacts ee and thereby opens the circuit between the pulsing contacts x and the line T_3 . Contacts ff of the relay R_7 are closed to maintain a holding circuit for relay R_7 by sustaining the ground initiated by contacts v .

The inch pulses are terminated in a similar manner when the sweep arm 56 comes in contact with contact w which grounds the coil of relay R_8 and serves to operate relay R_8 thereby opening the normally closed contacts gg which open the circuit between the pulsing contacts x and the line T_4 . Closing of contacts hh completes a holding circuit for relay R_8 by also sustaining a ground.

After the completion of the transmission of the foot and inch pulses, the cam 87a again operates switch S_7 closing contacts ii , but this time the contacts ii have no effect on the circuit as the switch S_3 is in contact with the insulating spot 148a on cam 128a and also because a ground is normally still sustained through contacts dd of relay R_6 . This insulating spot 148a is necessary because a momentary power failure could release all of the relays during the first revolution of cam 87a and then the subsequent operation of contacts ii would operate relay R_6 to start a false reading operation if switch S_3 were not released from ground by insulating spot 148a.

The respective cams continue to rotate until cam 128a has rotated to such a position that the latch 124 drops into notch 133. This returns switch S_8 to its normal position and opens contacts kk which interrupt the source of power to the motor 69 and the transformer 157. This operation of switch S_8 also serves to place the contacts jj in their normally closed position which returns the coil of relay R_5 to the lines T_3 and T_5 . The equipment is now in position for reception of a triggering pulse to commence a future reading operation.

It will be evident from the foregoing that our apparatus has many desirable features which adapt it for use in a wide variety of telemetering systems. Its application to remote liquid level tank gauging is only one of many industrial applications. It can be used for example to secure remote readings of temperatures, pressures, flow rates and like data, or the motion which is provided at a remote point can be used to facilitate automatic or semi-automatic control of industrial equipment or processing operations. The apparatus can be made more elaborate or can be simplified, in accordance with the requirements in each particular instance. For example, in the first embodiment described in some instances it may not be necessary or desirable to utilize code pulses transmitted before the indicating pulses. The transmission of code pulses can be omitted by eliminating notch 92 in cam 87 or by the simple expedient of adjusting the contact arm 151 whereby it immediately engages contact 155, before the code pulses are transmitted. For remote liquid level gauging it is desirable to transmit two separate series of pulses, one representing feet and the other inches by eighths. It will be evident however that these units are taken merely because of their standard use in tank level gauging, and that by simple changes the two series of pulses can be used to indicate various units of measure, such as meters and centimeters, degrees and minutes of angular displacement, and the like. In some applications where accuracy is not essential, a single train of pulses may be sufficient. Here again the apparatus can be adjusted to transmit a single train of pulses, instead of two trains, or if desired the apparatus can be simplified by eliminating the means incorporated for transmitting the second train.

We claim:

1. In telemetering transmitting apparatus of the type adapted to indicate the extent of displacement of an ele-

ment from a base position by a plurality of pulses transmitted to a remote receiving station, said apparatus comprising means including pulsing contacts for transmitting electrical pulses to the receiving station, a motor for driving the pulsing contacts, circuit means for energizing the motor, a first rotatable member adapted to be rotated in proportion to the displacement of said element, a second rotatable member cooperating with the said first member, a transfer gear connecting said members whereby each cycle of rotation of the first member serves to move the second member a fractional part of one revolution, a third rotatable member cooperating with the first and second members, means forming a motion transmitting connection between the third member and said motor whereby by said third member is rotated in synchronism with operation of the pulsing contacts, said third member in one revolution moving from a starting position through an angular distance to a base starting position, and then back to the starting position, contacts carried by the first and second members whereby the angular distances through which said contacts are displaced from said base position serve to indicate the displacement of said element from the base position in terms of coarse and fine units, an electrical contact carried by said third member and adapted to engage both of the contacts carried by first and second members during rotation of the third member, means for effecting control of said energizing circuit for the motor whereby the motor is cycled to drive said third member two complete revolutions from its initial starting point, selector means for effecting transmission of one series of pulses for the first revolution of said third member and a second series of pulses during the second revolution of said member, means controlled by the engagement of said contact means carried by the third member for terminating each series of pulses, whereby the first series of pulses indicates the position of the second member and the second series of pulses indicates the position of the first member, means for initiating transmission of a series of pulses while said third member is moving from its starting position to its base position to thereby effect identification of the transmitting station, and means for terminating said last named series of pulses prior to initiating transmission of a series of indicating pulses.

2. In telemetering transmitting apparatus of the type adapted to indicate the extent of displacement of an element from a base position by a plurality of pulses transmitted to a remote receiving station, said apparatus comprising means including pulsing contacts for transmitting electrical pulses to the receiving station, a motor for driving the pulsing contacts, circuit means for energizing the motor, a first rotatable member adapted to be rotated in proportion to the displacement of said element, a second rotatable member cooperating with the said first member, a transfer gear connecting said members whereby each cycle of rotation of the first member serves to move the second member a fractional part of one revolution, a third rotatable member cooperating with the first and second members, means forming a motion transmitting connection between the third member and said motor whereby said third member is rotated in synchronism with operation of the pulsing contacts, said third member in one revolution moving from a starting position through an angular distance to a base starting position, and then back to the starting position, contacts carried by the first and second members whereby the angular distances through which said contacts are displaced from said base position serve to indicate the displacement of said element from the base position in terms of coarse and fine units, an electrical contact carried by said third member and adapted to engage both of the contacts carried by the first and second members during rotation of the third member, means for effecting control of said energizing circuit for the motor whereby the motor is cycled to drive said third member two complete revolutions from its initial

starting point, means for effecting simultaneous transmission of two series of pulses during the first revolution of said third member, means controlled by the engagement of said contact means carried by the third member for terminating each series of pulses, whereby one series of pulses indicates the position of the second member and the other series of pulses indicates the position of the first member.

3. Telemetering apparatus as in claim 1 together with means for locking the transfer gear against rotation before transmission of the series of pulses serving to indicate the positions of the second and first members, said locking means including a cam driven by said motor.

4. Telemetering apparatus as in claim 2 together with means for locking the transfer gear against rotation before transmission of the series of pulses serving to indicate the positions of the second and first members, said locking means including a cam driven by said motor.

5. In telemetering apparatus of the type adapted to indicate the extent of displacement of an element from a base position by the pulses transmitted to a remote receiving station, said apparatus comprising means including pulsing contacts for transmitting electrical pulses to the receiving station through a communicating medium, a first member adapted to be rotated by an amount in proportion to displacement of said element, a second rotatable member, means forming a drive connection between said members whereby rotation of said first member through one complete revolution serves to advance the second member a fractional part of one revolution, the angular displacement of points on each member from a base reference position serving to indicate the displacement of said element in terms of coarse and fine units, a third member cooperating with the first and second members, motive means for driving the pulsing contacts and for rotating said third member to effect cyclic angular displacement of the same from a starting position through angles corresponding to the displacements of the first and second members from their base positions, said pulsing contacts being driven during the time said third member is being driven, means for connecting said pulsing contacts to the communicating medium between the transmitting and receiving station upon movement of said first and second members from their base positions, and means for disconnecting said pulsing contacts from said communicating medium when the third member passes through angles corresponding to the positions of the first and second members for terminating transmission of said pulses.

6. Telemetering apparatus as in claim 5 wherein one pulse is transmitted for each increment of displacement of said element and wherein said pulsing contacts are connected to said communicating medium at the beginning of a pulse.

7. Telemetering apparatus as in claim 5 together with means for causing simultaneous transmission of each series of pulses.

8. In telemetering transmitting apparatus of the type adapted to indicate the extent of displacement of an element from a base position by the use of pulses transmitted to a remote receiving station, said apparatus comprising pulsing contacts for transmitting electrical pulses through a communicating medium to a receiving station, a motor for driving the pulsing contacts, circuit means for energizing the motor, a first rotatable member adapted to be rotated a distance in proportion to the displacement of said element, a second rotatable member corresponding to the first member, a motion transmitting connection of the Geneva gear type connecting said members whereby for each cycle of rotation of said first member the second member is rotated a fractional part of a revolution during the last increment of said first member, a third rotatable member cooperating with both of said members, motion transmitting means connecting the third member to said motor whereby said third member is driven in synchronism with the generation of pulses, one

pulse being transmitted for each increment of displacement of said element, said pulsing contacts being driven continuously while said third member is being rotated, means for connecting said pulsing contacts to said communicating medium upon movement of said first and second members from a base position to commence the sending of two series of pulses to the receiving station, one series to indicate the position of said second member and the other to indicate the position of said first member, and means for discontinuing the sending of one of the series of pulses when the third member passes through an angle corresponding to the position of the second member, means for terminating the other series of pulses when the third member passes through an angle corresponding to the position of the first member and means for locking the Geneva gear against rotation during transmission of the series of pulses, said means including a movable latch having two operating positions, in one of which it locks the Geneva gear against rotation, and in the other of which it permits rotation of the transfer gear, and cam means driven by said motor and adapted to move said latch to its first named position for operation of the apparatus to transmit pulses to indicate the positioning of the second and first members.

9. Telemetering apparatus as in claim 8 wherein said means for locking the Geneva transfer gear serves to prevent errors in reading greater than one increment.

10. Telemetering apparatus as in claim 8 wherein said pulsing contacts are connected to said communicating medium during an open condition of said pulsing contacts.

11. Telemetering apparatus as in claim 8 together with means for causing simultaneous transmission of said series of pulses.

12. In telemetering transmitting apparatus of the type adapted to indicate the extent of displacement of an element from a base position by the use of pulses transmitted to a remote receiving station, said apparatus comprising pulsing contacts for transmitting electrical pulses to the receiving station, a motor for driving the pulsing contacts, circuit means for energizing the motor, a first rotatable member adapted to be rotated a distance in proportion to displacement of said element, a second rotatable member corresponding to the first member, a motion transmitting connection of the Geneva gear type connecting said members whereby for each cycle of rotation of said first member the second member is rotated a fractional part of a revolution during the last increment of said first member, a third rotatable member cooperating with both said members, motion transmitting means connecting the third member to the motor whereby said third member is driven in synchronism with the generation of the pulses, electrical contacts carried by the first and second members and positioned by the rotation of the same to indicate the angular position of each of said first and second members from a base point, contact means carried by said third member and adapted to engage the contacts on the first and second members, means controlled by engagement of the contacts carried by the third member with the contacts carried by the first and

50 second members for effecting termination of transmission of pulses, means to effect transmission of one series of pulses to indicate the position of the second member and another series to indicate the position of the first member during a complete cyclic movement of said third member, and means for locking the second member against rotation during transmission of the pulses, said locking means including a cam driven by said electric motor.

13. In telemetering transmitting apparatus of the type adapted to indicate the extent of displacement of an element from a base position by the use of pulses transmitted to a remote receiving station, said apparatus comprising pulsing contacts for transmitting electrical pulses to the receiving station, a motor for driving the pulsing contacts, circuit means for energizing the motor, a first rotatable member adapted to be rotated a distance in proportion

to displacement of said element, a second rotatable member corresponding to the first member, a motion transmitting connection of the Geneva gear type connecting said members whereby for each cycle of rotation of said first member the second member is rotated a fractional part of a revolution during the last increment of said first member, a third rotatable member cooperating with both said members, motion transmitting means connecting the third member to the motor whereby said third member is driven in synchronism with the generation of the pulses, electrical contacts carried by the first and second members and positioned by the rotation of the same to indicate the angular position of each of said first and second members from a base point, contact means carried by said third member and adapted to engage the contacts of the first and second members, means controlled by engagement of the contacts carried by the third member with the contacts carried by the first and second members for effecting termination of transmission of pulses, means to effect transmission of one series of pulses to indicate the position of the second member and another series of pulses to indicate the position of the first member during a complete cyclic movement of said third member, and means for locking the Geneva transfer gear against rotation during transmission of a series of pulses, said means including a movable latch having two operating positions, one of which locks the Geneva transfer gear against rotation, and in the other of which permits rotation of the transfer gear, and cam means driven by said motor and adapted to move said latch to its first named position before operation of the apparatus to transmit pulses to indicate the positioning of the second and first members.

14. In telemetering transmitting apparatus of the type adapted to indicate the extent of displacement of an element from a base position by the use of pulses transmitted to a remote receiving station, said apparatus comprising means adapted to be energized by a starting pulse, first and second movable members adapted to be moved a distance in proportion to the displacement of said element, means whereby displacement of said element moves the second member only a fractional part of the distance that the first member is moved, a third movable member adapted to move alongside said first and second members, motor means for moving said third member, means including a plurality of cams rotated by said motor means in synchronism with the movement of said third member, pulsing contacts operated by one of said cams, means operated by another of said cams for locking the second member against movement before transmission of said pulses, electrical pulses carried by the first and second members positioned by movement of the same to indicate the displacement of said first and second members from their base positions, contact means on said third member, means including relays connected to said pulsing contacts whereby upon movement of said third member there will be effected a transmission of a series of pulses to indicate the position of the first member and another series of pulses to indicate the position of said second member, and switch means connected to said relays and operated by another of said cams to de-energize said apparatus at the end of the reading operation.

15. Telemetering apparatus as in claim 14 together with means for causing simultaneous transmission of the series of pulses.

16. Telemetering apparatus as in claim 14 together with means for causing said pulsing contacts to transmit an identification code in the form of a series of pulses upon the energization of said apparatus.

17. Telemetering apparatus as in claim 16 together with means for causing sequential transmission of the series of pulses.

18. In telemetering transmitting apparatus of the type adapted to indicate the extent of displacement of an element from a base position by pulses transmitted to a remote receiving station, said apparatus comprising control means adapted to be energized by a starting pulse, pulsing

contacts for transmitting a series of electrical pulses to a receiving station, a motor for driving said pulsing contacts, circuit means connecting said motor to said control means whereby upon energization of said control means by said starting pulse said motor will be energized, a member adapted to be displaced a distance in proportion to the displacement of said element, another member cooperating with the first named member, motion transmitting means connecting the second member to said motor whereby said second member is driven in synchronism with the generation of pulses, circuitry including a relay for connecting the pulsing contacts to the receiving station, said relay including a pair of contacts connected in the circuitry connecting the pulsing contacts to the receiving station, said relay being energized upon energization of said control means to open said pair of contacts, switch means adapted to be operated by said motor to cause de-energization of said relay and closing of said pair of contacts to permit transmission of said electrical pulses to said receiving station, an electrical contact carried by the first named member and positioned by rotation of the same to indicate the position of the first named member, contact means carried by the second member and adapted to engage the contact on the first member to energize said relay and effect termination of the transmission of pulses.

19. Telemetering apparatus as in claim 18 wherein said switch means includes means to only permit operation of said switch means during an open condition of the pulsing contacts.

20. In telemetering apparatus of the type adapted to indicate the extent of displacement of an element from a base position by pulses transmitted to a remote receiving station, said apparatus comprising means including pulsing contacts for transmitting electrical pulses to the receiving station, a first member adapted to be rotated by an amount in proportion to the displacement of said element, a second rotatable member, means forming a drive connection between said members whereby rotation of said first member through one complete revolution serves to advance the second member a fractional part of one revolution, the angular displacement of points on each member from a base reference position serving to indicate the displacement of said element in terms of coarse and fine units, a third member cooperating with the first and second members, motive means for driving the pulsing contacts and for rotating said third member to effect cyclic angular displacement of the same from a starting position through angles corresponding to the displacements of the first and second members from their base positions, means for connecting said pulsing contacts to the receiving station during an open condition of said pulsing contacts and upon movement of said first and second members from their base positions for initiation of transmission of series of pulses, and means disconnecting said pulsing contacts from the receiving station when the third member passes through angles corresponding to the positions of the first and second members for terminating transmission of the series of pulses.

21. Telemetering apparatus as in claim 20 together with means for locking the second member against rotation during transmission of the series of pulses, said locking means including a cam driven by said electric motor.

22. Telemetering apparatus as in claim 20 together with means for causing simultaneous transmission of said series of pulses.
